HANGER FOR TROUSERS

Harry Stec, Rochester, N. Y.

Application May 2, 1938, Serial No. 205,415

1 Claim. (Cl. 223—96)

The object of this invention is to make a device that can be used for hanging trousers upside down, the device having two jaws between which are clamped the bottom of the trousers.

5 Another object of the invention is to provide a device in which a cam or eccentric is used for pressing the jaws together.

Another object of the invention is to locate this eccentric in the middle of the device, so that 10 it will draw together the wires by which the jaws are suspended.

These and other objects of the invention will be 15 illustrated in the drawing, described in the specification, and pointed out in the claim at the end thereof.

In the drawing:

Figure 1 is a side elevation of the device partly broken away.

Figure 2 shows a vertical section through the 20 device, the section being taken on the line 2x—2x of Figure 1.

Figure 3 shows a horizontal section, the section being taken on the line 3x—3x of Figure 2.

Figure 4 is a side elevation of the device, showing a modification of the device shown in Figure 1.

Figure 5 shows a vertical section, the section being taken on the line 5x—5x of Figure 4.

Figure 6 is a horizontal section on the line 6x—6x of Figure 5.

30 In the drawing like reference numerals indicate like parts.

In the drawing reference numerals 1 and 2 indicate the two jaws of the device, which are made preferably of wood. 3 indicates the hook by which the jaws are suspended, which hook is made preferably of one piece of wire bent to the desired shape. As shown in Figures 1 and 2, this hook has two members 4 and 5 joined together at 6. At the intermediate points indicated by reference numerals 7 and 8, the members 4 and 5 are flattened, but otherwise the wire is left round. The lower ends of the members 4 and 5 pass through the jaws 1 and 2 and are turned up at the bottom. These upturned ends are inserted 40 in sockets suitably provided in the wooden jaws. This gives a firm bearing of the wire members on the jaws. As above pointed out, the member 4 is flattened as indicated at 7, and to this member is fastened in any suitable way a metal strap 9, which strap encircles the member 5 at 8. The outer ends of this strap are pivotally connected to an eccentric 10, which is provided with a handle 11. As shown in Figure 5, this eccentric

10 can be moved from the dotted line position to the full line position, or vice versa. When in the dotted line position, the jaws 1 and 2 are released, so to speak, so that they can be spread apart for the insertion of the bottom of the trousers between them, and after the trousers are inserted between them the eccentric can be moved to the full line position, in which position it presses the members 4 and 5 together at the bottom and at the same time securely presses the jaws 1 and 2 together to clamp the bottom of the trousers between them. In order to give the eccentric 10 a firm bearing on the wire member 5, this member is flattened as indicated at 8, so that a broad, flat surface is presented to the bearing surface of the eccentric and thereby the locking of the members together is thus better secured.

In Figure 4 I have shown the jaws 1 and 2 suspended by a hook 13, made of flat wire, which 20 hook comprises the members 14 and 15 joined together at 16. These wires appear rectangular in section at 17 and 18 in Figure 6 and the corresponding wires in Figures 1 and 2 would appear in the same way if the section were taken 25 through the strap 9 or just above it. The lower ends of the members 14 and 15 are mortised into the jaws 1 and 2 and fastened therein in any suitable manner.

In use, the eccentric is placed in the dotted 30 line position as shown in Figure 5, and the lower ends of the trousers are inserted between the jaws when spread apart. The eccentric is then moved to the full line position, pressing the jaws together securely clamping the bottoms of the 35 trousers between the jaws, after which the hook can be engaged with any suitable support so that the trousers will hang at full length therefrom.

I claim:

The combination of a pair of parallel jaws, a 40 hook having two members for supporting the jaws, each of said members engaging one of the jaws, a strap fastened to one member of the hook and loosely embracing the other member of the hook, an eccentric pivotally mounted between the 45 two free ends of said strap, said eccentric bearing against the other member of said hook and being adapted when in one position to hold the two members of the hook and their jaws together and in another position being adapted to 50 release the jaws and the members of the hook.

HARRY STEC.
